SHOCK CUSHIONING PNEUMATIC PRESS

Stephen Lerma, Flushing, N. Y.

Application January 12, 1948, Serial No. 1,831

2 Claims. (Cl. 113—45)

1

This invention relates to an apparatus for controlling the operation of a pneumatic press and more particularly to mechanism for gradually increasing the magnitude of the impact on the work in a press during each power stroke.

In order to produce high grade formed articles, it is necessary that the various steps in forming the articles by the pressing method shall be accomplished under accurate control. It is also required that the pressing or deforming of a blank shall not be carried out at too great a rate of deformation. When the forming is carried out at too rapid a rate, there is produced an internal stress which either alters the material or even causes rupture of the material.

An object of this invention is to provide an improved multi-stage single stroke pneumatic press in which a composite plunger or working member may have an advance movement and then at desired points in the advancement of the composite plunger, increasing and pre-determined pressure stages are made available automatically to the maximum pressure of the press.

Another object of this invention is to provide an initial spring cushioned low pressure impact on the work by the composite plunger.

Another object of this invention resides in the provision of an inlet valve which is automatically opened to cause the fluid in the high pressure air cylinder to be delivered to a cushioning device at a desired stage of the working stroke of the composite plunger, and forming an intermediate stage pressing operation which may be varied and accomplished by opening the inlet valve at a pre-determined position in the stroke of the composite plunger.

Another object of this invention is to provide a combined pressure regulating device for controlling the flow of fluid under pressure to an auxiliary cushioning device and for operating a pneumatic press in step-by-step, stages in increasing pressures up to the maximum pressure of the press.

Another object of this invention is to provide a slideable cup shaped extension member on the composite plunger forming an intermediate pressure chamber, an air relief valve being in communication with the intermediate pressure chamber, whereby the air pressure in the intermediate pressure chamber may be varied to provide an intermediate pressure impact less than the full pressure plunger impact of the press.

With the above and other objects in view, the invention will be hereinafter more particularly described, and the combination and arrangement

2

of parts will be shown in the accompanying drawings and pointed out in the claims which form part of this specification.

Reference will now be had to the drawings, wherein like numerals of reference designate corresponding parts throughout the several views, in which:

Figure 1 is a front elevation of the pneumatic shock cushioning press, the plunger cylinder being shown in cross-section.

Figure 2 is a front elevation on an enlarged scale, the intermediate pressure chamber being shown in cross-section.

Figure 3 is a top plan view of a hand operated aid control valve.

Figure 4 is a side elevation, partly in cross-section of the control valve shown in Figure 3.

In the illustrated embodiment of the invention, the numeral 10 indicates a pneumatic press comprising a base 11 from which extends upwardly a frame 12 which supports a main air cylinder 13. The cylinder 13 is closed by a cover 14 having a boss 15 for guiding a plunger 16.

Inside the cylinder 13 is a piston 17 which is suitably secured to the upper end portion of the plunger 16. A coil spring 18 is interposed between the cover 14 and the piston 17 for supporting the plunger in upright position.

The piston 17 is actuated by compressed air which is supplied through air hose 20 and through a globe valve 21 which is suitably connected to an aperture 22 in the upper portion of the cylinder 13.

For the purpose of providing a safety feature in the operation of the press 10, there are two hand operated air control valves 23 of identical design and respectively secured at each side of the base 11.

Each valve 23 comprises a rectangular body 24 having an inlet 25 and an outlet 26. Resiliently supported in the body 24 by a spring 27 is a flat face valve 28 seated against the lower end of a tubular member or valve seat 29. Extending upwardly from the body 24 is a push rod 30 which is in alignment with the valve 28. At the lower end of the push rod 30 is a head 31 which is in contacting relation with the upper end of the valve 28.

A hand operated lever 32 is pivotally mounted on a pin 33 in a bracket 34 secured to the body 24. When the lever 32 is down pressed, it causes the push rod 30 to lower the right-hand valve 28 from its seat and to permit compressed air to pass through the inlet 25, through the valve body 24 and out through the outlet 26. The com-

pressed air then passes through a hose 35, through the left-hand valve 23, through a hose 36, to the globe valve 21.

The valves 23 must be operated simultaneously by both hands of the operator in order to supply compressed air to the plunger 16. This keeps the hands of the operator away from the upper and lower plate members of the die set 37, 38.

The piston 17 may however be actuated by compressed air which is supplied from a foot operated control valve 40 secured to the floor adjacent to the press 10. The control valve 40 may be of the type shown in Patent Number 2,388,560 and needs no further description.

It is to be noted that the air from the cylinder 13 is discharged through an aperture 41 in the cylinder wall when the upper face of the piston 17 passes below the aperture.

For the purpose of cushioning the shock of the upper die set plate member 37 against the work, I provide a cup shaped plunger extension 42 which is slidably mounted at the lower end portion of the plunger 16. The member 42 is supported on the plunger 16 by retaining pins 43 fixed in the member 42 and passing through slots 44 in the plunger 16.

An open coil compression spring 45 is interposed between the lower end of the plunger 16 and a horizontal surface in a recess or intermediate pressure chamber 46 in the plunger extension 42. The spring 45 maintains the horizontal surface of the recess 46 in the plunger extension 42 in spaced-apart relation from the lower end of the plunger.

It is to be noted that the compression spring 45 exerts a considerable pressure in a downward direction against the plunger extension 42 and when the plunger 16 lowers the upper die set member 37 against the work, a low pressure impact is exerted on the work by the spring 45 prior to the exertion of the full pressure plunger impact of the press 10. This low pressure impact takes place during the time it takes for the lower end of the plunger 16 to reach the upper surface of a boss or impact head 47 inside the plunger extension 42.

For the purpose of further cushioning the shock of the upper die set plate member 37 against the work, I provide an elongated passageway 48 in the plunger 16. The passageway 48 extends from the upper surface of the piston 17 down to valve chamber 49 inside the plunger 16. An inlet valve 50 is slidably mounted in the chamber 49 with the valve head 51 seated in a tapering valve seat 52. A coil spring 53 is interposed between the upper surface of the valve chamber 49 and the upper surface of the valve head 51.

It is to be noted that a valve operating screw 54 is threadably mounted in the boss 47 and may be adjusted with relation to the lower surface of the valve head 51 so that prior to the contacting relation of the lower surface of the plunger 16 with the upper surface of the boss 47, the screw 54 will raise the valve 50 off its seat and permit compressed air from the cylinder 13 to enter the intermediate pressure chamber 46 through the passageway 48.

It is to be noted that a relief valve 55 is suitably connected in communication with the recess 46. The valve 55 well known in the art, may be set to maintain the pressure in the intermediate pressure chamber to a predetermined pressure less than the air pressure above the piston 17, but producing a pneumatic pressure impact on

the work greater than the impact produced by the spring 45.

It is further to be noted that continuation of a single power stroke finally brings the full-pressure plunger impact on the work.

It will thus be noted that there has been provided a multi-stage impact cushioning pneumatic press comprising a single power stroke composite plunger adapted to deliver step-by-step increasing pressures on the work, so that the deformation or forming of the work will be gradual and prevent rupture of the material, and which will also increase the life of the die parts.

In operation, as the die parts 37, 38, are brought together, there is a compression of the spring 45, which results in a soft impact on the work.

The rising pin 54 opens the valve 50 and allows compressed air to enter the chamber 46, a predetermined amount of which is set to escape through the relief valve 55, thereby providing a higher and pre-determined impact on the work.

The relief valve aperture is then shut off by the lowered plunger 16, and a blow of full impact is delivered on the work.

Instead of bringing the die parts 37, 38, together with the full impact and taking a chance of damaging the material worked upon, this step-by-step impact arrangement subdivides the total impact into three stages.

In the arrangement shown, the relief valve 55 is connected below the lower face of the plunger 16 and can relieve the pressure only when the die parts 37, 38 are in operating relation, that is, only during the momentary period when the work is compressed.

It will be seen that this invention provides means for controlling the flow of a pressure fluid to and from a plunger-sustained cushioning device and is adaptable to various kinds of presses.

In practice, the lower end portion 57 of the plunger extension 42 is threaded to permit the upper die member 37 to be threadably adjusted thereon and then secured in position by a bolt 58.

Figures 1 and 2 show a pipe 60 connected to the lower portion of the plunger extension 42. The pipe 60 is in alignment with a pipe 56 for the valve 55.

A pressure gauge 61 is suitably secured to the pipe 60 to indicate the air pressure in the chamber 46. The operator adjusts the valve 55 to maintain a pre-determined pressure in the chamber 46. The size or area of the chamber 46 is made to give the desired impact on the work at this intermediate stage of each power stroke. The relief valve 55 operates when the high pressure inlet valve is open.

In accordance with the patent statutes I have described and illustrated the preferred embodiments of my invention, but it will be understood that various changes and modifications can be made therein without departing from the spirit of the invention as defined by the appended claims.

I claim:

1. In a multi-stage impact cushioning press having an air pressure cylinder, a piston slidable in said cylinder and comprising a plunger extending through one end of the cylinder, said plunger having a cup-shaped extension member slidably mounted at its lower end while retained thereon against disengagement, a compression spring in a chamber formed between said extension member and the lower end of said plunger and exerting pressure against the lower face of said plunger, said spring limiting the impact of said extension

member on the work, a spring-closed inlet valve slidably mounted in said plunger, means in said extension member adapted to open said inlet valve upon substantial compression of said first named spring, said valve when open admitting air under pressure from said cylinder to said chamber to cause controlled pneumatic pressure impact on the work, a pressure relief valve communicating with said chamber, an impact head on the extension member arranged to contact the lower face of said plunger after the inlet valve has been opened, and means for closing communication between the relief valve and the chamber just before the impact head engages the plunger.

2. In a multi-stage impact cushioning press having an air pressure cylinder, a piston slidable in said cylinder and comprising a plunger extending through one end of the cylinder, said plunger having a cup-shaped extension member slidably mounted at its lower end while retained thereon against disengagement, a compression spring in a chamber formed between an inner face of said extension member and the lower end face of said plunger and exerting pressure against the lower face of said plunger, said spring limiting the initial impact of said extension member on the work, a spring-closed inlet valve slidably mounted in said plunger, adjustable means in said cup-shaped

extension member adapted to open said inlet valve upon substantial compression of said first named spring, said inlet valve when open admitting air under pressure from said cylinder to said chamber to cause controlled pneumatic pressure impact on the work, an adjustable pressure relief valve communicating with said chamber, an impact head on the extension member arranged to contact the lower face of said plunger after the inlet valve has been opened, and means for closing communication between the relief valve and the chamber just before the impact head engages the plunger.
